UNITED STATES PATENT OFFICE.

BLAINE W. ODOM, OF DALLAS, TEXAS.

FOUNTAIN-PEN BLOTTING ATTACHMENT.

1,387,298.

Specification of Letters Patent. Patented Aug. 9, 1921.

Application filed February 14, 1921. Serial No. 444,741.

To all whom it may concern:

Be it known that I, BLAINE W. ODOM, a citizen of the United States, residing at Dallas, in the county of Dallas and State 5 of Texas, have invented new and useful Improvements in Fountain-Pen Blotting Attachments, of which the following is a specification.

The object of my present invention is the 10 provision of a simple and efficient blotting attachment for fountain pens and one that is adapted to be manipulated with great facility and is so constructed as not to detract from the appearance of the pen when used 15 in the ordinary well known manner.

To the attainment of the foregoing, the invention consists in the improvement as 20 hereinafter described and definitely claimed.

In the accompanying drawings, forming 25 part hereof:—

Figure 1 is a longitudinal diametrical section illustrative of so much of a fountain pen as is necessary to make clear the preferred embodiment of my invention.

Fig. 2 is a view showing my attachment 30 in side elevation as the same appears when its cap is removed to render the blotting member ready for use.

Fig. 3 is a side elevation of the complete 35 pen equipped with my novel attachment, and as the same appears with the pen in condition to be carried in the pocket.

Similar numerals of reference designate 40 corresponding parts in all of the views of the drawings.

The fountain pen includes the usual reservoir member 1 by which the pen point 2 is carried, and it also comprises a removable cover or guard member 3 for the pen point.

The guard member 3 is provided in its 45 outer end with a socket 4 to receive a threaded plug 5 which is preferably of hard vulcanized rubber. This latter construction is in accordance with my invention, and also in

accordance with the invention a stem 6, preferably of metal is provided with an enlargement 7 which is fixed in the longitudinal center of the plug 5 at the time of manufacture thereof. Mounted on and revoluble about 50

the stem 6 is a roller 8 of blotting paper or other appropriate blotting or ink absorbing material. The said roller 8 is molded or otherwise formed in one piece and is of truncated cone configuration for obvious 55 reasons. In order to assure free turning of the roller 8 about the stem 6, a washer 9 is

loosely mounted on the stem 6 and is interposed between the base of the roller 8 and the outer end of the plug 5. A washer 10 is also loosely mounted on the stem 6 at the 60 outer end of the roller 8, and the outer end of the stem 6 is upset as indicated by 11 in order to retain the said washer 10 in working position.

My improvement also includes a cap 12 65 that is frictionally or otherwise removably secured on the cover or guard member 3.

Manifestly when the cap 12 is removed to expose the roller 8, the said roller 8 may be conveniently rolled over the written matter 70 to be blotted, and this when the guard member 3 is positioned on the reservoir member 1 of the pen or is removed from the said reservoir member 1.

It will be apparent from the foregoing 75 that notwithstanding the utility of my novel attachment and the facility with which the said attachment may be employed, the attachment is simple and inexpensive in construction and is not liable to detract in any 80 measure from the finished and compact appearance of a fountain pen.

Having described my invention, what I claim and desire to secure by Letters-Patent, 85 is:—

1. A fountain pen attachment comprising a guard member in the outer end of which is a socket, a cap mounted on and removable from said guard member, a plug secured in the said socket of the guard member, a stem 90 having an enlargement at one end secured in the said plug and also having its outer end upset, a blotting roller mounted on and revoluble about the said stem, a washer loosely surrounding the stem and interposed 95 between the base of the roller and the said plug, and a washer loosely mounted on the stem and interposed between the outer end of the roller and the upset portion of the stem.

2. A fountain pen attachment comprising a guard member in the outer end of which is a socket, a cap mounted on and removable from said guard member, a plug secured in the said socket of the guard member, a stem 100 having an enlargement at one end secured in the said plug, and a blotting roller mounted and retained on and revoluble about the said stem.

In testimony whereof I affix my signature. 110

BLAINE W. ODOM.
